Brown Griswold.

UNITED STATES PATENT OFFICE.

EDWIN GILBERT, OF GEORGETOWN, CONNECTICUT, ASSIGNOR TO THE GILBERT & BENNETT MANUFACTURING COMPANY, OF SAME PLACE.

FENCE-POST.

SPECIFICATION forming part of Letters Patent No. 412,954, dated October 15, 1889.

Application filed February 25, 1889. Serial No. 301,046. (No model.)

To all whom it may concern:

Be it known that I, EDWIN GILBERT, of Georgetown, in the county of Fairfield and State of Connecticut, have invented a certain 5 new and useful Improvement in Fence-Posts, of which the following is a specification.

My improvement relates to fence-posts used in conjunction with a wire-fence web, which latter is secured to the post.

10 I will describe in detail a fence-post embodying my improvement, and then point out the novel features in the claim.

In the accompanying drawings, Figure 1 is a side elevation of a fence-post embodying 15 my improvement and a portion of a wire-fence web, together with a top rail. Fig. 2 is a section thereof, taken on the plane of the line $x x$, Fig. 1.

Similar letters of reference designate 20 responding parts in both the figures.

A designates a fence-post. This fence-post is made from a metallic tube. A slot a is formed in the tube, extending for a distance in the direction of the length of the tube and 25 having a closed lower end, but the upper end of which opens upon the top of the tube. A portion of the post a' , below the slot a , is unbroken and tubular. In the example of my improvement shown the lower end portion b of the tube is flattened out, so as to 30 form a driving-point. Combined with the post is a cap B , which cap may be secured upon the post by screw-threads, or otherwise. The cap B is provided with slots c , extending 35 vertically and arranged opposite each other, so that when the cap is upon the post the slots therein will be coincident with the slot a in the post. In the cap also is cast or other-

wise formed a horizontally-extending aperture d , which aperture is adapted to receive 40 a top rail C . The slots c in the cap in the example of my improvement shown open into the aperture d .

E designates a wire-fence web. This fence-web is to be received within the slots a of the 45 post, and may be secured therein by means of bolts or rivets passing through the post. The web also extends into the slots c in the cap. If the top rail C is slotted longitudinally upon one side, as it may be, the web E 50 will also extend into the slot in the top rail. In such case the web may be secured within the top rail by means of hooks, in a manner shown in United States Letters Patent No. 402,732, granted to me May 7, 1889. 55

In the construction of my improved fence-post I may use old boiler-tubes or any other iron tube, and saw the slot a therein. The cap B may be cast.

This post is very cheaply made, besides being 60 very durable, and is adapted to be readily combined with a wire-fence web and with a top rail.

What I claim as my invention, and desire 65 to secure by Letters Patent, is—

The combination, with a fence-post made of a single tube slotted longitudinally to receive a wire-fence web, of a cap for said post, also slotted to receive the wire web and provided with an aperture to receive a top rail, 70 substantially as specified.

EDWIN GILBERT.
